(57) **CLAIM**

We claim the ornamental design for a liquid cooling processor enclosure with frost facade, as shown and described.

DESCRIPTION

FIG. 1 is a front perspective view of the liquid cooling processor enclosure with frost facade comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof

FIG. 9 is an enlarged view taken from the indicated area in FIG. 8;

FIG. 10 is a cross-section taken from FIG. 1 in the direction of the arrows labeled FIG. 10; and,

FIG. 11 is an environmental view thereof depicting the liquid cooling processor enclosure with frost façade coupled over a processor.

The broken lines depict portions of the liquid cooling processor with frost façade and an environment of use and form no part of the claim.
